SHOE SEWING MACHINE

Raymond E. Hopkins, Rockland, Mass., assignor
to United Shoe Machinery Corporation, Paterson, N. J., a corporation of New Jersey

Application October 25, 1933, Serial No. 695,136

7 Claims. (Cl. 112—51)

The present invention relates to improvements in work guiding and channel forming devices for shoe sewing machines, and is herein disclosed as embodied in a sewing machine of the McKay type having a rotary shoe supporting horn and a reciprocating straight hook needle.

It is common practice to employ an edge gage on the work support of a sewing machine for spacing the seam uniformly the desired distance from the edge. An edge gage on a McKay shoe sewing machine cannot be supported on the work supporting horn of the machine because in supporting the shoe the horn is entirely surrounded by the shoe upper. The usual location for an edge gage on this type of machine, therefore, is on the presser-foot where, due to the nature of the machine, the manner of connection and adjustment has heretofore occasioned considerable difficulty. This difficulty is most troublesome on machines used in repair work where different styles and sizes of shoes operated upon require frequent adjustment of the position of the edge gage. It is also desirable for certain kinds of work to provide a groove in the outer surface of the shoe sole to conceal the stitches. When a work channelling knife is mounted on the machine to form the groove during operation of the stitch-forming devices, it also may interfere with the operation of the stitch-forming devices so as to cause irregularities in the seam and unequal spacings of the seam from the edge of the sole.

The objects of the invention are to provide novel and improved constructions and arrangements of parts including an edge gage and a channelling knife on this type of sewing machine which may readily be adjusted for different operating requirements as desired when used for repair work and, accordingly, a feature of the invention contemplates the provision, in a McKay type sewing machine having an edge gage on the presser-foot, of a threaded shaft on the presser-foot, so arranged as not to interfere with the operation of the machine, for adjusting the position of the edge gage relatively to the point of operation of the stitch forming devices.

In the specific embodiment of the invention as hereinafter illustrated, the edge gage is mounted on a threaded block slidable in a slot extending transversely to the line of feed in the presser-foot and the threaded shaft, mounted on the presser foot lengthwise of the slot, engages the threaded opening in the block to adjustably secure it in position. Convenient means is also provided for rotating the shaft to shift the edge gage supporting block along the transverse slot of the

presser foot. By so arranging the threaded shaft the thickness of the edge gage supporting portion of the presser-foot is not increased in weight and thickness to such an extent as to interfere with proper operation of the machine and the position of the edge gage may readily be adjusted even while the presser foot engages the work.

The above and other features of the invention, comprising a novel and improved work channelling knife for use with a machine of the type described, will be apparent to those skilled in the art from the following description taken in connection with the accompanying drawing, in which, Fig. 1 is a view in front elevation of a portion of a sewing machine embodying the features of the present invention; Fig. 2 is a view in side elevation of some of the parts illustrated in Fig. 1; Fig. 3 is a detail view on an enlarged scale, partly in section, of a portion of the machine; Fig. 4 is a detail plan view of the presser-foot of the machine; Fig. 5 is a sectional view taken along the line 5—5 of Fig. 4; Fig. 6 is a detail view in front elevation of the presser-foot; and Fig. 7 is a detail view in side elevation of the presser-foot.

In the machine illustrated, the shoe, indicated at 10, is supported on a work supporting horn 12 having a needle threading whirl at its upper end. The shoe is operated upon by stitch forming devices comprising a reciprocating straight hook needle 14, a shuttle 16, a feed point 18, and a presser-foot 20. The presser-foot 20 acts to secure the work against the tip of the horn 12 during operation of the needle. The shoe is intermittently released from the presser-foot and moved in the line of feed by the feed point 18 in substantially the same manner, except as hereinafter described, as in the machine described in the U. S. Patent to Leveque, No. 1,885,927, granted November 1, 1932. The presser-foot 20 is provided with a work channelling knife 22 and an edge gauge 24.

In the embodiment of the invention as herein illustrated, the edge gauge 24 is in the form of a roll mounted to rotate about a vertical axis on a screw 26 extending through a washer 27 and the roll, and engaging a threaded opening in a block 28. The block 28 is slidably fitted in a slot 30 in a laterally extending portion 32 of the presser foot. The block 28 is secured within the slot 30 of the presser foot by the threaded portion of a screw 34 loosely supported in horizontal bearings in the presser foot, and arranged lengthwise of the slot 30. The screw 34 extends through a threaded opening in the block 28, and when the

screw is rotated the block is caused to move along the slot. To prevent lengthwise movement of the screw, the head of the screw is engaged in a shouldered recess 36 in the presser foot, and 5 a nut 38 threaded onto the other end of the screw engages the outer surface of the laterally extending portion 32 of the presser foot. To rotate the screw, the nut 38 is knurled about its circumferential surface, and a lock nut 40 threaded 10 on the screw 34 frictionally engages the nut 38.

The edge gage roll is located, in the direction of feed, between the points of engagement of the channelling knife 22 and the feed point 18 with 15 the shoe, the movement of the shoe in the direction of feed being so guided that the smallest possible amount of movement at an angle to the line of feed will take place in the work at both points of engagement of the feed point and the 20 channelling knife when operating along the curved edge of the shoe at the toe. To prevent marring the edges of the work when the presser foot is raised and lowered during operation of the machine, the edge gage roll is bevelled about 25 its circumference and presents a smooth curved surface against which the work is pressed.

In order to adapt the machine for use in repairing shoes having the heels attached, particularly women's high heeled shoes, the manner 30 of mounting the presser foot on the machine of the Leveque patent has been changed to provide greater clearance for high heels and to permit sewing closer to the heel of the shoe than with the Leveque machine. The presser foot in the 35 present machine is secured to one end of a reciprocating presser foot bar 42 by a screw 44 passing through a slot 46 in the presser foot into a threaded opening in the bar. To prevent rotation about the screw 44, the presser foot is slotted and is engaged by a tongue 47 on the 40 presser foot bar. The presser foot bar is resiliently moved downwardly against the work by an arm 48 in which is mounted a stud 50 connected with the presser foot bar by a link 52 pivoted at its upper end on the stud 50 and at its lower 45 end to a second stud 54 secured in an enlargement of the presser foot bar 42. The presser foot is also provided with a portion 56 for compressing the seam to force the material of the 50 shoe against the stitches and close the channel formed by the channelling knife 22.

Due to the necessity in machines of the McKay type of operating the needle, feed point, and presser foot from the outer side of a shoe sole 55 which is supported by the rotary horn engaging the inside surface of the sole, the cutting action of the channelling knife 22 must take place during each cycle at some time at which it will not interfere with the operation of the other devices. 60 While the work is released by the presser foot, the feed point 18 acts to advance the work in the line of feed, but the force imparted to the work by the feed point is not great enough in this type of machine to provide reliable cutting 65 action when the knife is arranged to cut during the feeding movement.

To permit the knife to operate uniformly, the presser foot of the machine, herein illustrated, is raised somewhat higher than in the machine 70 of the patent above referred to so that the shoe will be substantially relieved from the dragging action of the knife during the feeding movement. At the end of the feeding movement of the shoe, while the feed point still remains in engagement 75 with the work, the presser foot is moved

downwardly, causing the knife to form a uniform groove of a depth equal to the distance below the under surface of the presser foot by which the knife projects. To regulate the horizontal position of the knife 22 on the presser foot, 5 the knife is secured to the presser foot by a screw 58 passing through an elongated slot 60 in the knife and into the presser foot. The presser foot is also formed with a slot 62 into which a rib on the channelling knife extends for 10 preventing relative angular movement of the knife and presser-foot. When the screw 58 is loosened, the knife 22 may be shifted on the screw to the desired position.

The nature and scope of the invention having 15 been indicated, and a machine embodying the several features of the invention having been specifically described, what is claimed is:

1. A shoe sewing machine having, in combination, a rotary horn, a straight hook needle, a feed point, a presser foot for securing the work against the horn, an edge gage, an edge gage support mounted to slide on the presser foot to position the edge gage relative to the point of operation of the needle in the work, and a threaded shaft 20 engaging the edge gage support to adjust when rotated the position of the edge gage support in its mounting on the presser foot.

2. A shoe sewing machine having, in combination, a rotary horn, a straight hook needle, a feed 30 point, a presser foot having a slotted portion extending transversely to the line of feed, a block provided with a threaded opening, a rotatable threaded shaft extending lengthwise of the slotted portion of the presser foot and engaging the 35 threaded opening in the block for holding the block in the slotted portion, an edge gage carried by the block, and means for rotating the threaded shaft to shift the edge gage towards and from the point of operation of the needle.

3. A shoe sewing machine having, in combination, a rotary horn, a straight hook needle, a feed point, a presser foot having a slotted portion extending transversely to the line of feed, a block provided with a threaded opening and guided by 45 the slotted portion of the presser foot, a rotatable threaded shaft extending lengthwise of the slotted portion and engaging the opening in the block to hold the block in the slotted portion, an edge 50 gage roll rotatably mounted on the block for guiding the edge of the work, and an adjusting member on the threaded shaft at a point readily accessible while the work is secured by the presser foot for rotating the rod to shift the edge gage roll towards and from the point of operation 55 of the needle.

4. A shoe sewing machine having, in combination, a rotary horn, a straight hook needle, a feed point, a presser foot having a slotted portion extending transversely to the line of feed, a work 60 channelling knife on the presser foot for forming a stitch receiving groove in the work in advance of the point of operation of the needle, a block provided with a threaded opening, a rotatable threaded shaft arranged lengthwise of the slotted 65 portion of the presser foot and engaged in the threaded opening in the block for holding the block in the slotted position, an edge gage carried by the block, and means for rotating the threaded shaft to shift the edge gage towards 70 and from the channelling knife.

5. A shoe sewing machine having, in combination, a rotary horn, a straight hook needle, a feed point, a presser foot having a slotted portion at one side extending transversely to the line of 75

feed, a work channeling knife on the presser foot for forming a stitch receiving groove in the work in advance of the point of operation of the needle, means on the other side of the presser foot for compressing the seam, a block provided with a threaded opening, an edge gage carried by the block, a rotatable threaded shaft arranged lengthwise of the slotted portion of the presser-foot and engaged in the threaded opening in the block for holding the block in the slotted portion, and means projecting beyond the slotted portion of the presser-foot comprising means for rotating the threaded shaft to shift the edge gage towards and from the channeling knife.

15 6. A shoe sewing machine of the McKay type having, in combination, a rotary horn arranged to extend within and support a shoe being operated upon, stitch forming and work feeding devices acting on the outside of the shoe sole and including a straight hook needle, a presser foot movable towards and from the outer side of the sole to intermittently clamp and release the shoe on the horn, a feed point for feeding the shoe when released by the presser-foot, a work chan-

neling knife on the presser-foot for forming a uniform stitch receiving groove in the outer side of the shoe sole when the presser foot moves against the shoe and for disengaging the shoe during the feeding movement of the feed point. 5

7. A shoe sewing machine of the McKay type having, in combination, a rotary horn arranged to extend within and support a shoe being operated upon, stitch forming and work feeding devices acting on the outside of the shoe sole and including a straight hook needle, a presser foot movable towards and from the outer side of the sole to intermittently clamp and release the shoe on the horn, a feed point for feeding the shoe when released by the presser-foot, a work channeling knife on the presser foot for forming a uniform stitch receiving groove in the outer side of the shoe sole when the presser foot moves against the shoe and for disengaging the shoe during the feeding movement of the feed point, 10 and means carried by the presser foot to close the channel over the seam formed by the stitch forming devices. 15
